CLAIM

The ornamental design for blender attachment, as shown and described.

DESCRIPTION

FIG. 1 is a perspective view of a blender attachment, showing our new design in an embodiment;

FIG. 2 is a front view of the embodiment shown in FIG. 1; FIG. 3 is a back view of the embodiment shown in FIG. 1; FIG. 4 is side view of the embodiment shown in FIG. 1; FIG. 5 is another side view of the embodiment shown in FIG. 1;

FIG. 6 is a top view of the embodiment shown in FIG. 1; FIG. 7 is a bottom view of the embodiment shown in FIG. 1;

FIG. 8 is another perspective view of the embodiment shown in FIG. 1, as shown in a blender environment;

FIG. 9 is a perspective view of a blender attachment, showing our new design in another embodiment;

FIG. 10 is a front view of the embodiment shown in FIG. 9; FIG. 11 is a back view of the embodiment shown in FIG. 9; FIG. 12 is side view of the embodiment shown in FIG. 9; FIG. 13 is another side view of the embodiment shown in FIG. 9;

FIG. 14 is a top view of the embodiment shown in FIG. 9; FIG. 15 is a bottom view of the embodiment shown in FIG. 9; and,

FIG. 16 is another perspective view of the embodiment shown in FIG. 9, as shown in a blender environment. The broken lines in the figures are for environmental purposes only and form no part of the claimed design.

The stippling shown in the embodiments of FIGS. 1-8 represents a contrast in appearance and/or material from the other claimed portions of the design in the embodiments of FIGS. 9-16.

(Continued)

The stippling shown in the embodiments of FIGS. 9-16 (which is a lighter relative to the stippling in the embodiments of FIGS. 1-8) represents a metallic surface such as stainless steel.
